UNITED STATES PATENT OFFICE

JOSÉ MAS BADÍA, OF BARCELONA, SPAIN

LOOM

Application filed May 10, 1930, Serial No. 451,383, and in Spain August 14, 1929.

It is well known that when by accident there is only partial entry of shuttles into their boxes in looms having a plurality of shuttles, accidents occur which often prove serious.

According to the invention each shuttle under normal conditions automatically penetrates by simple means into the interior of the corresponding box. The means employed consists essentially of a thrusting member for the shuttles, which has an angular shape and is adapted to rock on a pivot pin mounted on the loom frame, which thrusting member is subject to the action of a spring which tends to maintain the thrusting member in a determined position, in such manner that in the downward movement of the boxes as a whole, if a shuttle be left in a slightly abnormal position by not completely entering into the box, that shuttle encounters the thrusting member which moves upon its pivot pin in overcoming the action of the spring, the spring then causing the thrusting member to rock in an opposite direction, forcing the shuttle towards its box until it comes into the normal position.

The invention comprises the constructional features hereinafter described with reference to the accompanying drawing.

Figure 1 is a view in vertical projection of the corresponding parts, when the machine is working normally.

Figure 2 is a view showing what happens if a shuttle does not completely re-enter its box.

Figure 3 represents in horizontal projection a detail hereinafter described.

The frame 1 of the loom has pivoted at 2 the thrusting member 3 having an angular form and on one of whose sides a rod 4 is supported, subjected to the action of a compression spring 5 through which it passes, and placed within a support 6, the said spring ensuring that the upper part or side 45 of the angle 3 always remains very nearly in a horizontal position.

Boxes 7, 8, 9, 10 correspond to the shuttles 11, 12, 13, 14 and form an integral casing which as it is known has an up and down movement. If the shuttles enter quite nor-

mally into their boxes, as indicated in Figure 1, the device remains inactive, while the said boxes descend as a whole. If a shuttle, for example, the shuttle 13 rests abnormally a little outside its box 9, then on the descent 55 of the boxes the shuttle 13 strikes against the thrusting member which is made to rock backwards on its pivot pin 2 in overcoming the action of the spring 5; but this spring by its reaction tends to make the thrusting 60 member 3 rise, which, by sliding against the point of the shuttle 13 and by forcing it back, makes it slide and enter completely into the box 9.

It is preferable to mount on the upper 65 part of the thrusting member 3 as shown in the horizontal projection, also represented in Figure 3, a groove 15 for the reception of the thread which comes out of the butt-cop, in order to avoid mishaps in working. 70

The apparatus described is susceptible of modifications in the form and disposition of its component parts without the variation affecting the principle of the invention.

I claim:—

1. In looms provided with shifting shuttle boxes a plurality of shuttles, a device for ensuring the complete entry of shuttles into the shuttle boxes and comprising a member movably connected to the loom frame and 80 means for supporting the said member resiliently in its initial position so that it presents a surface lying parallel to the axes of the shuttles in the path of a shuttle projecting from the boxes which yields and takes 85 up an inclined position to force the shuttle into its box in its continued downward movement.

2. In looms provided with shifting shuttle boxes a plurality of shuttles, a device for ensuring the complete entry of shuttles into the shuttle boxes and comprising an angular member pivoted to the loom frame so as normally to present one surface parallel with the axes of the shuttles and a second surface 95 transversely thereto, and a spring applied at the rear of the second surface to maintain the first surface resiliently in its initial position.

3. In looms provided with shifting shuttle 100

boxes a plurality of shuttles, a device for ensuring the complete entry of shuttles into the shuttle boxes and according to claim 2, having a bearing bracket upon the loom frame, a plunger rod slidably supported in the said bracket and bearing upon the rear of the second surface of the said member, a collar on the said plunger rod and a compression spring coiled upon the said plunger rod between the bearing bracket and the said collar.

4. In looms provided with shifting shuttle boxes a plurality of shuttles and a device for ensuring the complete entry of the shuttles into their boxes during the movement of descent of the latter, comprising an element disposed adjacent the path of the boxes and whose operative surface is, when in the normal position, parallel to the axes of the shuttles, said element being mounted to pivot downwardly about an axis transverse to the axes of the shuttles, and a spring which tends to maintain said element in the normal position and elastically resists the downward movement of the element, so that a shuttle projecting from its box in the descent of the box depresses the element to a position in which the operative surface is inclined to the axis of the shuttle and presses the latter home under the action of the spring.
